RELAY SYSTEM

Karl H. Sommermeyer, Evanston, Ill., assignor to
G-M Laboratories, Inc., Chicago, Ill., a corpora-
tion of Illinois

Application February 17, 1936, Serial No. 64,262

9 Claims. (Cl. 175—320)

The present invention relates generally to elec-
trical relay systems, and relates more particu-
larly to an improved electrical relay of the self-
latching type and improved operating circuits
therefor.

5 Relays of the type having a mechanical latch
for holding the armature in an operated position
often are used in systems where the relays are
required to preserve the connections which they
have established despite any temporary failure
10 of power. They, also, have been used in systems
where the relays are required to operate only in-
frequently and where it, therefore, was desirable
that the relays maintain their operated positions
15 mechanically in order to permit the magnets to
be left de-energized.

It is desirable that the relay itself, in operating
should interrupt its own coil circuit so as to avoid
useless energization of its coil and the consequent
20 waste of electric power. It is also desirable that
the electro-magnet which operates the relay
armature continue to hold the same in its oper-
ated condition until after the armature definitely
has been latched or secured mechanically.

25 If this is not insured, the magnet may de-ener-
gize before the armature is latched, thereby
permitting the armature to return to its original
position. In so returning it re-energizes its mag-
net and the action is repeated again and again.
30 This faulty "self-cycling" action is sometimes re-
ferred to as "buzzing" or "telegraphing" depend-
ing upon the speed at which it takes place. In
accordance with one manner of carrying out the
present invention I insure that the armature is
35 latched before the energizing magnet is de-ener-
gized by compelling that sequence of operation
mechanically. To accomplish this mechanical
control of the sequence of operation I may cause
the contacts which de-energize the armature mag-
net to be actuated by the latch itself as the latter
40 slips into latching position. And I, also, provide
a "lag-loop" or "closed coil time delay" circuit
on the armature magnet so that the armature
magnet does not release the armature until a
period of time after the supply of power to the
45 energizing coil of the magnet is discontinued.

50 It is desirable, also, for certain purposes to
have a latching relay operate certain of its con-
tacts with a time delay, that is, open or close one
or more contacts after allowing a period of time
to elapse after the initial energizing of the arma-
ture magnet. In accordance with one manner of
carrying out the present invention I provide con-
tacts operated by the armature of the relay and
other contacts operated by the latch itself and I

5 provide interlocking electrical connections be-
tween these contacts and the magnets operating
the armature and latch to cause the latch itself
to delay its movement into latching position, sep-
arate the load contacts being actuated by the 5
armature and the latch.

10 It is further desirable that the latch should
impose a minimum of restraint upon the opera-
tion of the armature. To this end I employ the
same interlocking electrical connections above 10
mentioned to energize the latch magnet simul-
taneously with the armature magnet so as to
eliminate entirely all friction in the latch mech-
anism.

15 In the foregoing statements, I have used the 15
terms "armature" and "latch" for designating
certain elements by the characteristic functions
which they perform in the specific operational
sequences in which they are mentioned. A latch
20 relay may employ a symmetrical latch construc-
tion comprising two similar elements each of
which elements functions either as a latch or an
armature. The symmetrical arrangement per-
mits the two functions of latch and armature re-
25 spectively to be exchanged between these two sim-
ilar elements and it, also, makes the device
adaptable to a greater variety of control schemes.

30 Objects of the present invention include the
provision of an improved latch relay and system
for controlling it and the provision of a time de-
lay action in a latch relay to aid the operation of
the relay itself and to provide various time de-
layed control functions.

35 Other objects and advantages will become ap-
parent as the description proceeds.

40 In order better to acquaint those skilled in the
art with the teachings and practice of the pres-
ent invention, I now shall describe certain speci-
fic embodiments thereof, reference being had to
the accompanying drawings forming a part of 40
this specification and in which:

45 Fig. 1 is a perspective view of a latch type relay.

Fig. 2 illustrates the mechanical construction
and operation of the relay, and illustrates dia-
grammatically one circuit arrangement in which
it may be used.

Fig. 3 is an "across the line" diagram or line
diagram, of the circuit of Fig. 2.

Fig. 4 illustrates a system embodying the latch
relay of Fig. 1 together with the circuit employing
50 the interlocking connections which provide the
time delay action and which serve to eliminate
all friction in the latch.

Fig. 5 is an "across-the-line" diagram of the
circuit of Fig. 4.

Fig. 6 illustrates a modification of the system of Fig. 3.

Fig. 7 is an "across-the-line" diagram of the circuit of Fig. 6.

5 Referring to Figs. 1 and 2, the latch relay there-in shown comprises two electro-magnets designated generally by reference numerals 11 and 12. These magnets have independent magnetic circuits, separate coils 13 and 14, separate armatures 15 and 16 and contacts providing separate contact gaps 19, 20, 21 and 22. These "contacts" consist of cantilever spring blades which carry contact buttons at their ends as shown. Preferably the blades may be arranged in a number of 10 stacks as shown in Fig. 1. A single stack is shown on each magnet in Fig. 2 to facilitate the illustration. The armatures are provided with conical restoring springs 23 and 24, which aid the contact springs in tending to move the armatures into normal positions from which they may 15 be attracted into "drawn up" positions by their magnets.

The two magnets 11 and 12 are held together by means of a metal strap or tie bar 26 in such 20 positions relative to each other that the axes about which their armatures 15 and 16 rotate in operation are substantially parallel. Preferably the tie bar 26 is non-magnetic. The armatures 15 and 16 are provided with bars 27 and 28 which 25 move therewith. These bars 27 and 28 preferably are non-magnetic and they interfere with each other in such a manner that only one of the two armatures 15 and 16 of the magnets 11 and 12 may occupy its normal position at one time.

30 Referring more particularly to Fig. 2, the bar 27 is secured to the armature 15 of the magnet 11 and is configured to provide a latch portion or interfering portion 31 which extends radially from the axis of rotation of its own armature 15, 35 but extends in a direction substantially perpendicular to a similar latch portion or interfering portion 32 of the bar 28. This portion 31 is located at the end of the bar 27 between the coils 13 and 14. These radial portions 31 and 32 provide the interference between the armatures which already has been referred to. They interfere so as to provide the latching or blocking action whereby one armature, when occupying its released or normal position prevents the other 40 armature from leaving its drawn up position.

In Fig. 2, the armatures 15 and 16 and their associated bars 27 and 28 shown in the full lines with the armature 16 of the magnet 12 in its normal or released position, and the armature 15 of the magnet 11 latched thereby in its drawn-up position. The operation of the latching mechanism is substantially as follows:

45 When the coil 14 of the magnet 12 is energized, it attracts its armature 16 and draws it into its drawn-up position indicated in the dotted lines, thereby bringing the radial portion 32 into the position 32-A. In moving into the position 32-A, the portion 32 swings about the axis of rotation of the armature 16 and slides along the portion 31 of bar 27. In so doing the end of said portion 32 moves in a direction substantially parallel to the surface of the portion 31 of the bar 27. The portion 31 and the armature 15 of the magnet 11 therefore remains substantially stationary during the motion of the armature 16 and the magnet 12. When the portion 32 reaches the position 32-A, shown in dotted lines, it no longer blocks the motion of the portion 31, which, therefore, immediately moves under force of its 50 own restoring spring 23 as well as under the force

of its contacts 19 and 21, to bring the portion 31 into the position 31-A shown in the dotted lines. This abrupt and positive action of the latch is due in part to the sharply squared ends of the latch portions 31 and 32. The portion 31 when in the position 31-A blocks the portion 32 in the position 32-A so as to latch the armature 16 of the magnet 12 in its drawn-up position.

55 As shown in Fig. 1, the magnet 11 conveniently may be provided with two sets of contacts to provide contact gaps 19 and 21. In Fig. 2, the contacts on each magnet are shown arranged in a single stack for purpose of illustration. One set of the contacts, or one contact gap, on each magnet is of the normally open type so as to be open 10 when the armature is in its released position. Thus, the contact gap 19 of the magnet 11 is open 15 when the armature 15 occupies its normal or released position. Similarly, the contact gap 20 of the magnet 12 is open 20 when the armature 16 thereof occupies its normal position. Contacts 21 and 22 are load contacts.

The circuit of Fig. 2 is more simply illustrated in the "across-the-line" diagram, or line-diagram of Fig. 3. This diagram attempts only to illustrate the electrical arrangement and makes no attempt to illustrate any mechanical relationships of the elements except by legends. Thus the legend L₁ is applied to the coil and contact gaps of 25 the magnet 12, while the legend L₂ is applied 30 to the coil and contact gap of the magnet 13. The same reference numerals indicate the same 35 parts or elements in Figs. 2 and 3.

The coil 13 of the magnet 11 is shunted by a 40 resistor 29 and the combination of these two is 35 connected in series with the normally open contact gap 20 of the magnet 12, a normally open push button switch 35 and a battery 36. Similarly the coil 14 of the magnet 12 shunted by a resistor 30 and the combination of these two, is 45 connected in series with the normally open contact gap 19 of the magnet 11, push button switch 37 and the battery 36. Thus when the armature 15 of the magnet 11 is in its drawn-up position as shown in the full lines of Figure 2, the armature 45 50 55 60 65 70 75 80 85 90 95 100 105 110 115 120 125 130 135 140 145 150 not be de-energized until after the latching action has been accomplished. Similarly, the push button 35 may next be closed to return the armatures 15 and 16 to the position shown in the 5 full lines of Fig. 2.

The contacts which provide the contact gaps 21 and 22 may be of either the normally open or the normally closed type and may be utilized for controlling one or more load circuits in any 10 known manner.

A further provision for insuring that the relay will be positive in operation consists in subjecting the armature of the relay to a magnetic time delay which holds the armature in its picked up 15 position for a short period of time after the power is disconnected from its coil circuit, so as to further insure that the armature will be positively latched before it is released by its magnet; that is, to insure that the armature will be positively latched before it tends to move back to the 20 released position.

When the coil circuit of a magnet is disconnected from the power supply by the contacts in the manner already described, the magnetic 25 field thereof immediately begins to collapse or decay. In so doing, it generates or induces in the winding of the coil a voltage which tends to force an electric current in such a direction as to oppose the collapse or decay of the magnetic field. 30 The voltage thus induced in the coil will produce current provided there is a closed circuit in which the current may flow.

In the system of Figs. 2 and 3, for example, resistor 29, being connected across the terminals of 35 the coil 13, provides the closed circuit necessary for the current to flow. This circuit consists simply of the coil 13 and resistor 29. This current absorbs the energy of the magnetic field and dissipates it as heat resulting from the current flowing in the resistance circuit. The fact that this 40 current opposes the decay of the magnetic field tends to prevent the collapse of the flux and causes the field to decay more slowly than it would if this current did not flow. The current 45 in the coil decreases with time according to the relation expressed by the well known logarithmic decay curve. When the magnetic field decreases to that value at which it will no longer hold the armature in its drawn up position, the armature tends to move out of that position.

The rate of decay or collapse of the magnetic field may be decreased by decreasing the resistance which shunts the relay coil, by decreasing the residual air gap of the relay's magnetic circuit (when the relay armature is in its drawn up 50 position), or by increasing the ampere turns of excitation of the coil (by changing the coil design or increasing the voltage of its power supply). The specific means for providing this magnetic time delay of the relay forms no part of the present invention inasmuch as such means are well known in the art. Relays arranged to execute a magnetically delayed action in this manner are sometimes referred to as "lag-loop" 55 relays. Another method of providing this "lag-loop" operation consists in providing a coil section separate from the operating coil. This separate coil section may be short circuited, or otherwise provided with a closed circuit, and may consist of a single turn of large cross section in the form of a perforated copper slug.

The time delay action insures proper operation as follows: Assuming that the armatures 15 and 16 of the latch relay of Fig. 2 are in the positions shown therein in full lines, the armature 16 may

be operated by energizing its coil 14 from the battery 36 by closing the push button switch 37. The armature 16 draws up and in so doing unlatches the armature 15 in the manner already described so that the armature 15 immediately 5 begins to move towards its released position. In so doing it both latches the armature 16 and opens its contact gap 19 to disconnect the coil 14 from the battery. If because of misadjustment of the relay, or for any other reason, the 10 contact gap 19 should open before the latch portion 31 of the armature 15 gets into position to block the latch portion 32, of the armature 16 the relay can operate properly only if the armature 16 is prevented from releasing too quickly. 15 By retarding the decay of the magnetic flux of the magnet 14, the release of the armature 16 is delayed so that it is at rest in its drawn up position for a short period of time after the contact gap 19 opens. And if the contact gap 19 for any 20 reason should open before the armature 16 reached its picked up position, the delay in the collapse of the magnetic flux would actually prolong the period of acceleration of the armature towards its picked up position, prolong the period during which it is attracted by its magnet. Thus the magnet 14 continues to attract the armature 16 even after the battery is disconnected therefrom at the contact gap 19. Even 25 a very short prolongation of the attraction and holding of the armature 16 by its magnet after the contact gap 19 opens gives the armature 15 ample time and opportunity to move to its released position so as mechanically to latch the armature 16 in the latter's drawn up position.

In Fig. 4, I have illustrated a new and novel circuit for a latch relay. Therein, a latch relay very similar to the one illustrated in Fig. 2 has magnets 43 and 44 and interfering armatures 45 and 46. The armature 45 operates contacts 40 which provides a contact gap 49 which is closed when the armature 45 is in its released position. Similarly the armature 46 operates contacts which provide the contact gap 50 of the same type. Push button switch 55 is adapted, by virtue of the circuit connections to connect the coil of the magnet 43 to a power supply 54 and, also, to connect the coil of the magnet 44 to the same power supply through the contact gap 49. Similarly a push button switch 56 is adapted to connect the coil of the magnet 44 to the power supply 54 and, also, to connect the coil of the magnet 43 to the power supply through the contact gap 50. The coils of the magnets 43 and 44 are provided with shunt resistors 57 and 58 respectively.

Assuming that the relay is in the position shown in Fig. 4 with the armature 46 occupying its released position, the push button switch 56 may be closed to operate the relay. This immediately energizes both of the coils of the latch relay. The armature 45 being substantially in its drawn up position and, therefore having a very short air gap ordinarily will take up its slack motion before the magnetic field of the magnet 44 builds up sufficiently to initiate the motion of the armature 46. The armature 45 being attracted by its magnet so as to take up the slack in the latch, removes the friction load from the armature 46 which otherwise would be imposed by the latch. This materially improves the ease of operation of the latch relay and under certain conditions reduces the power required for its operation. When the armature 46 picks up it opens the contact gap 50 so as to disconnect the 75

power from the coil of the magnet 43. The magnet 43 will not release the armature 46 immediately because of the "lag loop" time delay provided by the resistor 57 shunting its coil. When the armature 45 does move to its released position it serves to latch the armature 46 in the latter's picked up position.

Load contacts providing contact gaps 51 and 52 may be operated by the two armatures 45 and 46. The time delay action just described to which the latch relay is subjected in the system of Fig. 3 causes a delay between the closing of the push button switch 56 and the operation of the load contact gap 51 operated by the armature 45. Similarly a delay is provided between the closing of the push button switch 55 and the operation of the load contact gap 52.

Fig. 6 illustrates a modification of the system of Fig. 4 wherein contact gaps 47 and 48 have been added to the respective magnets 43 and 44. These additional contact gaps are of the type which are open when the armatures operating them are in their released positions. The contact gap 47 is connected between the push button switch 56 and the coil of the magnet 44, and similarly the contact gap 48 is connected between the coil of the magnet 43 and the push button switch 55. Thus in Fig. 6, the push button switch 55 is adapted to connect the coil of the magnet 43 to the power supply 54 through the contact gap 48 and, also, to connect the coil of the magnet 44 to the power supply through the contact 49. Similarly the push button switch 56 is adapted to connect the coil of the magnet 44 to the power supply 54 through the contact gap 47 and, also, to connect the coil of the magnet 43 to the power supply through the contact gap 50. The operation is as follows: Assume that the armatures 45 and 46 are in the positions in which they are shown in Fig. 6. When the push button switch 56 closes both magnet coils are energized magnet 43 attracts its armature 45 which is already held by the latch. Armature 46 picks up, and opens the contact gap 50. This disconnects the coil of the magnet 43 from the power supply 54, but the magnet 43 continues to hold up its armature 45 for a short time due to the delay in the collapse of the magnetic flux imposed by the lag loop arrangement of the magnet 43. This time delay imposed by the magnet 43 delays the release of the armature 45 and the operation of its load contacts 51. At the end of this time delay period the armature 45 releases and in so doing opens the contact gap 47 which in turn disconnects the power supply from the magnet 44. The magnet 44 then continues to hold the armature 46 for a short period of time to give the armature 45 ample time to release and block the armature 46. When the magnet 44 finally releases the armature 46, the armature 46 drops against the latch which holds it in its picked up position. A similar action occurs when the push button switch 55 is closed.

The circuits of Figs. 4 and 6 are more simply illustrated in the "across-the-line" diagrams, or "line-diagrams" of Figs. 5 and 7. The line diagrams attempt only to illustrate the electrical arrangement and circuit relationships of the apparatus and make no attempt to illustrate any mechanical relationships of the elements or parts except by legends. The legend L₁ is applied to the coil and contact gaps of the magnet 44, while the legend L₂ is applied to the coil and contact gaps of the magnet 43. The same reference numerals indicate the same parts in Figs. 4, 5, 6 and 7.

73 While I have shown and described certain

specific embodiments of my invention, it will be apparent to those skilled in the art that the same is by way of illustration only, and that the invention is capable of numerous variations and modifications. Therefore, I do not wish to be limited except by the scope of the appended claims.

I claim:

1. In combination, a first armature, a second armature, each of said armatures having a drawn-up and a released position and being movable therebetween, a first electromagnet and a second electromagnet for said first and second armatures respectively, each electromagnet being adapted when energized to move its armature to the drawn-up position, interfering portions on said armatures adapting each armature when in its released position to block the movement of the other armature from its drawn-up to its released position, contacts providing a contact gap operated by said first armature which is closed when said first armature is in its released position and open when said first armature is in its drawn-up position, control means connected to the first electromagnet, said control means, also, being connected to the second electromagnet, through said contact gap.

2. In combination, a first armature, a second armature, each of said armatures having a drawn-up and a released position and being movable therebetween, a first electromagnet and second electromagnet for said first and second armatures respectively, each electromagnet being adapted when energized to move its armature to the drawn-up position, interfering portions on said armatures adapting each armature when in its released position to block the movement of the other armature from its drawn-up to its released position, contacts operated by said first armature which are closed when said first armature is in its released position and open when said first armature is in its drawn-up position, first control means connected to said first electromagnet, said first control means, also, being connected to said second electromagnet through said contacts, and second control means connected to said second electromagnet.

3. In combination, a first armature, a second armature, each of said armatures having a drawn-up and a released position and being movable therebetween, a first electromagnet and a second electromagnet for said first and second armatures respectively, each electromagnet being adapted when energized to move its armature to the drawn-up position, interfering portions on said armatures adapting each armature when in its released position to block the movement of the other armature from its drawn-up to its released position, first contacts operated by said first armature which are closed when said first armature is in its released position and open when said first armature is in its drawn-up position, second contacts operated by said second armature which are open when said second armature is in its released position and closed when said second armature is in its drawn-up position, and control means connected to said first electromagnet through said second contacts and connected to said second electromagnet through said first contacts.

4. In combination, a first armature, a second armature, each of said armatures having a drawn up and a released position and being movable therebetween, a first electromagnet adapted when energized to move said first armature to its drawn up position, a second electromagnet in-

cluding a coil and adapted when said coil is energized to move said second armature to its drawn up position, said second electromagnet including means for preventing said second armature from beginning to move towards its released position until a period of time elapses after power is disconnected from said coil, first contacts operated by said first armature which are closed when said first armature is in its released position and open when said first armature is in its drawn up position, second contacts operated by said second armature which are open when said second armature is in its released position and closed when said second armature is in its drawn up position, and control means connected to said first electromagnet through said second contacts and connected to said coil of said second electromagnet through said first contacts.

5. In combination, a first armature, a second armature, each of said armatures having a drawn up and a released position and being movable therebetween, a first electromagnet adapted when energized to move said first armature to its drawn up position, a second electromagnet including a coil and adapted when said coil is energized to move said second armature to its drawn up position, said second electromagnet including means for decreasing the rate of collapse of the magnetic field thereof, first contacts operated by said first armature which are closed when said first armature is in its released position and open when said first armature is in its drawn up position, second contacts operated by said second armature which are open when said second armature is in its released position and closed when said second armature is in its drawn up position, and control means connected to said first electromagnet through said second contacts and connected to said coil of said second electromagnet through said first contacts.

6. In combination, a first armature, a second armature, each of said armatures having a drawn up and a released position and being movable therebetween, a first electromagnet adapted when energized to move said first armature to its drawn up position, a second electromagnet including a coil and adapted when said coil is energized to move said second armature to its drawn up position, said second electromagnet including means tending to maintain the magnetic field thereof after said coil thereof ceases to receive electric power therefor, first contacts operated by said first armature which are closed when said first armature is in its released position and open when said first armature is in its drawn up position, second contacts operated by said second armature which are open when said second armature is in its released position and closed when said second armature is in its drawn up position, and control means connected to said first electromagnet through said second contacts and connected to said coil of said second electromagnet through said first contacts.

7. In combination, a first armature, a second armature, each of said armatures having a

drawn-up and a released position and being movable therebetween, a first electromagnet adapted when energized to move said first armature to its drawn up position, a second electromagnet including a coil and adapted when said coil is energized to move said second armature to its drawn up position, said second electromagnet including means for opposing the collapse of the magnetic field thereof, first contacts operated by said first armature which are closed when said first armature is in its released position and open when said first armature is in its drawn up position, second contacts operated by said second armature which are open when said second armature is in its released position and closed when said second armature is in its drawn up position, and control means including at least one source of power for simultaneously (1) connecting said first electromagnet through said second contacts to a source of power to energize said first magnet 20 to operate the same, and (2) connecting said coil of said second electromagnet through said first contacts to a source of power to energize said coil to produce a magnetic field in said second electromagnet in excess of the value required for magnetically holding said second armature in its drawn up position.

8. In combination, a first armature, a second armature, each of said armatures having a drawn-up and a released position and being movable therebetween, an electromagnet for said first armature adapted when energized to move said first armature to its drawn up position, interfering portions on said armatures adapting each armature when in its released position to block the movement of the other armature from its drawn up to its released position and means operable when said electromagnet is energized for opening the coil circuit thereof and for insuring that said first armature is positively blocked against moving to its released position before it is released by said electromagnet, said means including contacts operated by said second armature and including, also, means for opposing and retarding the collapse of the magnetic field of said electromagnet.

9. In combination in a latch relay and a control system therefor, a first armature, a second armature, each of said armatures having a drawn up and a released position and being movable therebetween, an electromagnet for said first armature adapted when energized to move said first armature to its drawn up position, interfering portions on said armatures adapting each armature when in its released position to block the movement of the other armature from its drawn up to its released position, means for energizing said magnet at least momentarily, and means operable when said magnet is energized tending to insure that said first armature is positively latched by the second armature, said last means including means for opposing and retarding the collapse of magnetic flux of said electromagnet.
